UNITED STATES PATENT OFFICE

W. H. LAUBACH, OF PHILADELPHIA, PENNSYLVANIA.

IMPROVED APPARATUS FOR CARBURETING GAS.

Specification forming part of Letters Patent No. 64,776, dated May 14, 1867.

To all whom it may concern:

Be it known that I, W. H. LAUBACH, of Philadelphia, in the county of Philadelphia and State of Pennsylvania, have invented a new and Improved Method of Regulating the Flow of Gas and Improving its Quality; and I do hereby declare that the following is a full, clear, and exact description thereof, which will enable others skilled in the art to make and use the same, reference being had to the accompanying drawings forming part of this specification.

This invention relates to a method by which the common street-gas is improved or enriched by passing over it hydrocarbon liquid, and to the manner in which the flow of the gas is regulated; and the invention consists in providing suitable vessels and chambers, pipes and cocks, whereby I am enabled to greatly improve the quality of the gas, and to regulate the flow thereof by a float and valve, in the manner hereinafter more fully described.

Figure 1 represents a reservoir of volatile hydrocarbon liquid. Fig. 2 represents a vessel containing hydrocarbon liquid, over which the gas passes to the regulator. Fig. 3 is a horizontal section of the same on the line *xx*. Fig. 4 is the regulator, showing the regulating-valve, the cistern and float, and the gas-passages. Fig. 5 is a horizontal section of the same through the line *yy*.

Similar letters of reference indicate like parts.

A is the regulator. *A'* represents a vessel, which contains volatile hydrocarbon liquid; it is a reservoir, from which a suitable quantity is discharged into the vessel below, marked *B*. The gas enters this vessel through the pipe *C*, and, following the spiral passage-way formed by the scroll in the interior of the vessel, marked *C'*, in contact with the liquid, it becomes loaded or saturated therewith, and is

discharged from thence with the regulator through the pipe *D*. *E* represents a central pipe, with an aperture through its upper end, through which the gas passes. The size or area of this aperture is regulated by a valve, *F*, which is conical in shape, and which is attached to a float, *G*, and moves up and down with it. This float may be suspended from above, and adjusted for a certain pressure, forming a chamber within, into which the gas is discharged from the pipe *E*. The cistern or annular space around the pipe *E* (marked *H*) is filled with water to about as far as is indicated in the drawing by the line *k*. When the pressure of the gas increases or diminishes the float *G* will rise or fall, and consequently the aperture through the pipe *E* will be enlarged or diminished as the conical valve rises or falls with the float. The gas is discharged from the regulator through the pipe *J* into the service-pipe.

It will be seen that the gas, after traversing through the spiral channel *C'*, (receiving thereby an additional supply of carbon,) is controlled and regulated in its discharge by its own pressure, and the pressure is easily increased or diminished by properly weighting or adjusting the float *G*, by which arrangement the consumption of the gas may be greatly economized.

What I claim as new, and desire to secure by Letters Patent, is—

1. I claim the carbureting-vessel *B*, in combination of the regulator *A*, substantially as described.

2. I claim the combination of regulator *A* and the hydrocarbon-vessel *B*, substantially as described.

W. H. LAUBACH.
